UNITED STATES PATENT OFFICE.

GEORGE E. FRIESEN, OF NORTH YAKIMA, WASHINGTON.

VACUUM GASOLENE-PUMP.

1,351,510.

Specification of Letters Patent. Patented Aug. 31, 1920.

Application filed December 23, 1918. Serial No. 268,022.

To all whom it may concern:

Be it known that I, GEORGE E. FRIESEN, a citizen of the United States, residing at North Yakima, in the county of Yakima and State of Washington, have invented a new and useful Vacuum Gasolene-Pump, of which the following is a specification.

The device forming the subject matter of this application is adapted to be employed for dispensing gasolene and like liquids, and one object of the invention is to provide novel means whereby the supply of liquid to a measuring tank, the amount of liquid delivered from the tank, and the suction applied to the tank, may be controlled simultaneously.

Another object of the invention is to provide a device of the class mentioned wherein the purchaser can ascertain by inspection that an honest transaction has been effected, as to the amount of liquid delivered.

A further object of the invention is to improve the means for controlling the suction which is applied to the tank.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in longitudinal section, a portion of a structure embodying the improvements hereinafter alluded to; Fig. 2 is a top plan showing the sleeve which is placed about the tank, at times; Fig. 3 is a top plan wherein parts are omitted; Fig. 4 is an elevation showing the complete structure; and Fig. 5 is a sectional detail illustrating the valves.

In carrying out the invention there is provided a support, which may be variously constructed. The support may include a base 1 on which rests a tubular pedestal 2. The pedestal 2 supports a tank 3 including a bottom 4, a top 5, a transparent shell 6 located between the top and the bottom,

gaskets 7 interposed between the ends of the top, on the one hand, and the bottom 4 and the top 5 on the other hand, and draw bolts 8 connecting the top and the bottom. The shell 6 of the tank is marked as shown 60 at 9, to indicate the capacity of the tank. When the structure is not in use, a protecting sleeve 10, shown in Fig. 2 and in Fig. 1, may be locked about the shell 6, the ends of the sleeve being engaged by the top 5 and 65 by the bottom 4. The sleeve 10 preferably consists of hingedly connected parts, as shown in Fig. 2.

The top 5 carries a housing 11. A bracket 12 extends across the bottom of the housing 70 11 and is terminally secured to the top 5. A plunger 14 is mounted to reciprocate in the bracket 12 and constitutes a portion of a float 15 operating in the housing 11. On the upper end of the plunger 14 there is 75 a valve 16 adapted to coöperate with the lower end of an elbow 17 assembled with the top of the housing 11. The outer end of the elbow 17 is united by a coupling 18 with a suction pipe 19 prolonged downwardly within the pedestal 2, as indicated in Fig. 1.

A casing 20 is interposed in the suction pipe 19 within the pedestal 2 and is provided with a lateral air inlet 22. A three-way valve 21 is journaled for rotation in the casing 20 and may be variously constructed. The three-way valve 21 may have a straight passage 23 and a curved passage 24.

The numeral 25 denotes a combined supply and discharge pipe connected at its upper end with the bottom 4 of the tank 3 and communicating with the tank. A casing 26 is interposed in the pipe 25 and carries a lateral pipe 27 supplied with a hand valve 28. A hose 29 is connected to the pipe 27. The pedestal 2 is provided with a swinging door 30, and at the lower edge of the door, a notch 31 is formed in the pedestal 90 2. The free end of the hose 29 may be mounted in the notch 31, when the hose is not in use, and, when desired, practically the entire length of the hose may be housed in the pedestal 2. A valve 40 is journaled in 95 the casing 26 and is provided with a straight passage 32 and with a curved passage 33.

An arm 34 is secured to the valve 40, the valve 21 being operated by means of an arm 35. A connection 36 is supplied, the same 110

including angularly disposed parts 37 and 38, the arms 34, 35 being pivoted as indicated at 41 to the part 37 of the connection. The connection 36, and, more specifically, 5 the part 38 thereof, carries a handle 39 which is accessible from the outside of the pedestal 2.

- Let it be supposed that the valves 40 and 21 are arranged as shown in Fig. 5.
- 10 Then, the air inlet 22 is closed by the valve 21, the passage 23 communicating with the suction pipe 19. Similarly, the pipe 27 and the dispensing hose 29 are closed by the valve 40, the passage 32 being in communication with the parts of the pipe 25. If suction is applied by way of the pipe 19, to the tank 3, gasoline or other liquid will be drawn into the tank, through the pipe 25. When the liquid has accumulated to a considerable extent in the tank, the float 15 will rise, and the valve 16 will close the suction pipe 19, thereby preventing liquid in the pipe 3 from being drawn out through the suction pipe.
- 15 By means of the handle 39, the connection 36 and the arms 34 and 35, the valves 40 and 21 may be set in such a way that the curved passage 23 in the valve 21 will establish communication between the air inlet 22 and that portion of the pipe 19 which leads from the casing 20 to the tank 3, the lower portion of the pipe 19 being closed off, so that there is no suction upon the tank. It will be obvious that air now is admitted 20 to the tank by way of the inlet 22, the passage 23 in the valve 21, the upper part of the pipe 19, the coupling 18 and the elbow 17, thereby venting the tank, so that a measured quantity of liquid may be dispensed.
- 25 When the valve 21 is operated as above described the valve 40 is rotated so that the

lower portion of the pipe 25 is cut off, no more liquid being delivered into the tank 3. The curved passage 33 in the valve 40 is brought into communication with the pipe 45 27 and the upper part of the pipe 25, and the liquid within the tank 3 can flow away through the upper part of the pipe 25, the passage 26 in the valve 21, the pipe 27 and the dispensing hose 29, it being possible to 50 control the amount of liquid dispensed by manipulating the valve 28, the quantity of liquid supplied being determined by an inspection of the graduations 9 on the transparent shell 6 of the tank 3.

Having thus described the invention, what is claimed is:—

In a device of the class described, a tank; a source of liquid supply; a dispensing outlet; a first valve establishing communication between the source and the tank, and between the tank and the outlet, at different times; a source of suction supply for the tank; an air inlet; a second valve establishing communication between the source 65 of suction supply and the tank, and between the air inlet and the tank, at different times; a third valve coöperating with the source of suction supply to open and close the same; a float operatively connected with 70 the last specified valve and responsive to changes of level in the tank; and means for operating the first and second valves simultaneously.

In testimony that I claim the foregoing 75 as my own, I have hereto affixed my signature in the presence of two witnesses.

GEORGE E. FRIESEN.
